Primary Examiner — Caron D Veynar*Assistant Examiner* — Katrina N Gonzalez(74) *Attorney, Agent, or Firm* — Edward S. Sherman(57) **CLAIM**

The ornamental design for a cookware lid vent, as shown and described.

DESCRIPTION

FIG. 1 is a perspective view of the “cookware lid vent” in the closed position, showing my new design;

FIG. 2 is a perspective view thereof in the open and vented position;

FIG. 3 is a right side elevation view thereof in the closed position of FIG. 1; the left side elevation view being the mirror image thereof,

FIG. 4 is a top plan view thereof;

FIG. 5 is a bottom plan view thereof;

FIG. 6 is a back elevation view thereof;

FIG. 7 is a front elevation view thereof; and,

FIG. 8 is a front elevation view thereof in the open position of FIG. 2.

The dot-dash broken lines in FIGS. 1, 2, 4, 5, 7 and 8 are shown for the purpose of illustrating the boundaries of internal portions which form no part of the claimed design.
